UNITED STATES PATENT OFFICE.

DANIEL M. RUGG, OF CLEVELAND, OHIO, ASSIGNOR TO THE GAS MACHINERY COMPANY, OF CLEVELAND, OHIO, A CORPORATION OF OHIO.

COKE AND GAS OVEN.

1,393,455.

Specification of Letters Patent. Patented Oct. 11, 1921.

Application filed August 30, 1917. Serial No. 188,924.

To all whom it may concern:

Be it known that I, DANIEL M. RUGG, a citizen of the United States, resident of Cleveland, county of Cuyahoga, and State of Ohio, have invented new and useful Improvements in Coke and Gas Ovens, of which the following is a specification, the principle of the invention being herein explained and the best mode in which I have 10 contemplated applying that principle, so as to distinguish it from other inventions.

My invention relates to apparatus for the production of gas and coke.

The object of my invention is to provide 15 an oven structure which may be used in connection with a fuel gas supply which, as well as the air, will require preheating, or in which a coke oven gas which needs no preheating may be used in connection with 20 an air supply suitably preheated.

The said invention consists of means hereinafter fully described and particularly set forth in the claims.

The annexed drawings and the following 25 description set forth in detail certain means embodying my invention, the disclosed means, however, constituting but one of various forms in which the principle of the invention may be employed.

90 In said annexed drawings:

Figure 1 represents a fragmentary longitudinal vertical section of a gas oven embodying my invention and taken upon the planes indicated by lines I—I in Fig. 2.

35 Fig. 2 represents a fragmentary transverse section taken through the heating units and upon the planes indicated by lines II—II in Figs. 1 and 3.

40 Fig. 3 represents a fragmentary horizontal section taken upon the plane indicated by lines III—III, in Fig. 2.

Fig. 4 represents a broken horizontal section taken in the planes indicated by the lines IV—IV, Fig. 1.

45 The illustrated embodiment of my invention comprises the usual masonry structure and auxiliary parts forming a plurality of parallel coking chambers 1, 1, Fig. 3. Between each two adjacent coking chambers is 50 a series of heating units 2, 2. Each of these heating units consists of two vertical chambers 3 and 4 separated from each other at the bottom and connected at the top as shown in Fig. 1. Each heating unit of any 55 given series is independent of every other of

such series, being separated from each other by the vertical walls 5.

Below these coking chambers and series of heating units is a plurality of regenerators 6, 6, arranged in pairs of separate and independent sections 7, 7. The bottoms of alternate regenerator pairs 6 communicate with two suitable ducts 8 and 8' by means of ports and ducts 7¹, 7² and 7³, Fig. 1, which act alternately as outlets for waste gases in the 65 usual manner, as will be readily understood by those skilled in the art.

One of the regenerators 7 of each regenerator pair 6 is connected with one of the combustion chambers of two heating units located 70 upon opposite sides of the coking chamber located immediately above such regenerator pair, by means of passages 10, 10, and the other regenerator 7 of the same pair 6 of regenerators is also connected with the same 75 two chambers of these same two units by means of the passages 11, 11. The chambers of any one unit are thus connected with regenerators located upon opposite sides of the vertical median plane of the said units. A 80 construction is thus provided which permits the reversal of the direction of flow of the gases, whereby the regenerator may be alternately heated by the waste gases, and then such heat used for heating such gaseous 85 products as may subsequently be caused to pass therethrough.

It will thus be noted that the apparatus comprises the combination of a plurality of coking chambers, a plurality of heating 90 units, the coking chambers and the heating unit series occurring alternately with reference to each other in the oven structure, each unit comprising two chambers, a plurality of pairs of regenerators each consisting of two separate and independent regenerators, connections between said regenerators and heating units such that gases may be passed through alternately occurring regenerators and through all the heating units 100 and then from the latter out through the remaining regenerators, and also in the reverse of such described direction; each such chamber being connected with a pair 7, 7, of regenerators and each regenerator of such pair 105 being connected with two such chambers.

One of the chambers, therefore, constitutes a combustion chamber while the gas is traveling in one direction and the other chamber connected therewith forms merely 110

an outlet duct for the gases of combustion during such period. When the gases are traveling in the opposite direction, the other of said chambers forms a combustion chamber and the first-mentioned chamber forms a duct for the outlet of the gases of combustion.

When the available fuel gas is a cold gas requiring preheating, the above-described apparatus is used and operated as follows:

One regenerator 7 of alternately occurring pairs 6 is connected with the atmosphere through the flue 8' and the other regenerator of each of these pairs of regenerators is connected by any suitable means with the source of cold fuel gas supply. The remaining regenerators are connected with the other of the waste gas flues. Air and gas are now passed upwardly through the first-named regenerator sections and emerge from the passages 10 and 11 where they are mixed and burned in the various combustion chambers immediately connected with those passages whence they pass downwardly through the other chambers of the heating units and out through the passages 10 and 11 thereof which act as outlets, into the said remaining regenerators, thus heating the checkerwork of the latter. The operation now being reversed, the pairs of regenerators which were previously heated are now respectively used as air and gas heating devices, and the first-named regenerators are heated, as will be readily understood, by the waste gases.

In addition to the above-described elements of the device, however, I also supply a separate and independent series of connections consisting of pipes 12 and 13 running beneath the heating units, pipes 12 being provided with a plurality of burners or gas nozzles 14, discharging into alternately occurring combustion chambers of any given series of heating units, and pipes 13 being similarly provided with gas burners or gas guns discharging into the remaining combustion chambers as shown in Fig. 3. These pipes are of course all connected with a common supply, suitable valves (not shown) being provided for the required control as will be understood.

When a gas requiring no preheating is used, it is supplied to the combustion chambers by means of these pipes 12 and 13 and when this is done, both regenerators 7, 7, of

the pairs 6 of regenerators which were used for preheating air and gas are used for heating air solely. It will be understood, of course, that when the fuel gas from the pipes 12 and 13 is used, only one of the two pipes 12 and 13 supplies gas at one and the same time, the other being cut off at such time so that as before only one of the two chambers of each heating unit acts as a combustion chamber at any one time. In other respects the apparatus operates as before, the same reversal being resorted to as will be understood.

From the above description it will appear that the construction which I have provided lends itself readily for use in connection with either a supply of gas requiring preheating or not, with the attendant economical advantages, which will be readily understood by those skilled in the art.

What I claim is:

1. In apparatus for the production of gas and coke, the combination of a coking chamber; heating units respectively located upon opposite sides of said chamber and each consisting of two connected combustion chambers; a pair of regenerator sections, one of said combustion chambers of each such heating unit being provided with an outlet; ducts arranged to connect each of the other chambers of said heating units with each of said regenerator sections; and means independent of said ducts for introducing fuel gas into said last-named combustion chambers.

2. In apparatus for the production of gas and coke, the combination of a coking chamber; heating units upon opposite sides of said chamber and each consisting of two connected combustion chambers; a pair of regenerator sections, one of said combustion chambers of each such heating unit being provided with a pair of outlets; ducts arranged to connect each of the other chambers of said heating unit with each of said regenerator sections; two additional pairs of regenerators, the respective pairs of outlets arranged to connect with the respective pairs of said two additional pairs of regenerators; and means independent of said ducts for introducing fuel gas into the last named combustion chambers.

Signed by me, this 21st day of August, 1917.

DANIEL M. RUGG.
